UNITED STATES PATENT OFFICE.

WILLIS M. HALL AND WILSON K. ELDRIDGE, OF WATERBURY,
CONNECTICUT.

CUT-OUT.

SPECIFICATION forming part of Letters Patent No. 736,598, dated August 18, 1903.

Application filed February 2, 1903. Serial No. 141,624. (No model.)

To all whom it may concern:

Be it known that we, WILLIS M. HALL and WILSON K. ELDRIDGE, citizens of the United States, residing and having our post-office addresses at Waterbury, in the county of New Haven and State of Connecticut, have invented certain new and useful Improvements in Cut-Outs; and we declare the following to be a full, clear, and exact description of the invention, such as will enable others skilled in the art to which it appertains to make and use the same.

Heretofore in the operation of both main and branch cut-outs, especially on large sizes, a considerable amount of difficulty has been encountered by reason of the impossibility of making sufficiently close and permanent connections between the main electric wires and the terminal binding-posts.

Our invention relates to new and useful improvements in electrical cut-outs; and its object, among other things, is to provide means for forming a close and permanent connection between the wires carrying the main current and the terminal binding-post, means for making all connections in the device free and clear from the surface of the non-conducting plate to which the several parts of our device are attached, and, further, to so construct the several parts that they can be economically constructed and readily assembled.

To these and other ends our invention consists in the cut-out having certain details of construction and combination of parts, as will be hereinafter described, and more particularly pointed out in the claims.

Referring to the drawings, in which like numerals and letters of reference designate like parts in the several figures, Figure 1 is a perspective view of a cut-out embodying our improvements. Fig. 2 is a side elevation of the preferred form of binding-clamp. Fig. 3 is a ground plan thereof. Fig. 4 is a ground plan of the cap to said clamp. Fig. 5 is a side elevation of a modified form of clamp. Figs. 6 and 7 are side elevations illustrating two constructions of a combined binding post and clamp; and Fig. 8 is a longitudinal sectional

elevation of our improved device, taken upon line *xx* of Fig. 1.

In the cut-outs heretofore constructed much difficulty has been encountered in making close and permanent connections between the main wires and the terminal binding-posts, this being especially true in cut-outs of large size, and, again, a further difficulty is encountered in that the connections between the main wires and terminal binding-posts have usually been beneath the surface of the non-conducting plate to which they are attached, this construction concealing the connection and rendering it extremely difficult to detect defects in workmanship or material, and when such defects exist the cut-outs fail to operate at all and if operated do so in an inefficient manner. We have overcome these objections in our device by providing means whereby the connections will be both close and positive, and all of the parts are above the non-conducting plate to which the device is attached.

In carrying out our invention we provide a plate *G* of non-conducting material, to which is affixed one or more main binding-posts *A*, which are secured to the plate *G* by the screws 14 and 15, which pass through holes 22. Upon either side of said main binding-posts are the terminal binding-posts *E*, which are also secured to the plate *G* by the screws 6, and connecting these binding-posts are the fuses *I* and *J*, which are respectively secured to said main binding-posts by screws 12 and 13 and to the terminal binding-posts by screws 4. Leading from the terminal binding-posts *E* are the branch wires 10 and 11. We make a permanent and rigid connection between the main wire *F* and main binding-posts *A*, and our preferred means for accomplishing this end consists of a clamp *B*, having a recess 17 therein forming a solder-chamber, and flanges 9, closing the ends thereof. Secured to the bottom of said clamp *B* by the screws 16 is the cap *C*, through which are a plurality of holes 3 opening into the chamber 17. This clamp is secured to the base 8 of the binding-post *A* by the screws 2. The main wire is permanently secured to this clamp by

removing the insulation about the end thereof for a distance equal to the width of said clamp and then inserting the same within the clamp between the flanges 9. The cap C is then placed in position, and solder or other material is poured into the chamber 13 through the holes 3 in a liquid state, the liquid being of such consistency that it will flow freely and fill in all of the open space in the chamber 17, thus uniting the clamp and main wire into one solid mass. If, perchance, the wire should be slightly smaller than the open space between the flanges 9, putty or some other pliable material is worked around the outside of said wire to prevent the liquid from escaping from the chamber 17. After the molten metal has cooled the clamp is secured in position on the arm 8 and a rigid and permanent connection is made between said main wire and the binding-post A. From the main binding-post the current is divided and passes through the fuse J upon one side through the terminal post E into the branch wire 11 and there conducted to its point of distribution and on the other side through the fuse I, binding-post E, and branch wire 10. The method heretofore in general use for making solder connections for branch cut-outs has been to first strip the insulation from the main and branch wire, and then after scraping and cleaning the same they have been coiled around each other, after which heat is applied to said coiled part and when sufficiently heated have been secured together by means of solder. This operation has been found defective in that the wires become more or less smutted by the heating-flame and prevents the solder from making a perfect connection, which imperfect connection permits the wires to become loosened in time, thereby creating a resistance through the arcs that are formed and frequently when the wires are adjacent to combustible material causes a fire; but by the use of our device these difficulties are overcome, the main wire being inclosed within the clamp and cannot be smutted, but a clean surface is presented to the solder, and the resulting connection is a positive and permanent one, the wires and clamp becoming a single unitary mass.

A modified form of clamp is shown in Fig. 5, in which a solder-chamber is formed in both the parts B and C'. In Fig. 6 we have illustrated a combined clamp and binding-post, in which it is designed to attach the main wire to said post mechanically without the aid of molten metal. This is accomplished by providing the opening 26 in the binding-post A and the set-screw 7, which impinges upon the main wire after

it is inserted within said opening, this binding-post being secured to the plate G by set-screws entering the tapped holes 18 and 19.

In Fig. 7 we have illustrated a clamp which is secured directly to the base 8 of the binding-post A by the screws 20, thus obviating the use of the cap C. (Illustrated in Fig. 2.)

By the improved construction of this cut-out currents of electricity may be deflected by the use of any standard make of non-arching fuses through the branch wires without the usual difficulty of installment. Either of the forms of lugs or clamps herein shown can be used with other forms or kinds of binding-posts, and we do not, therefore, limit ourselves to the exact construction of the posts and clamps as herein shown.

There are many minor changes and alterations that can be made within our invention aside from those herein suggested, and we would therefore have it understood that we do not limit ourselves to the exact construction herein shown and described, but claim all that falls fairly within the spirit and scope of our invention.

Having fully described our invention, what we claim as new, and desire to secure by Letters Patent, is—

1. In an electric cut-out, the combination with a binding-post; of a two-part clamp designed to be secured over the main wire, one of said parts being arched and recessed to form a solder-chamber, the ends of which comprise fitting-ribs, the other of said parts being provided with solder-holes opening into said solder-chamber; means for securing said parts together over said wire; and means for fastening said clamp to said binding-post, all constructed substantially as described.

2. In an electric cut-out, the combination with the base G; of the binding-post A attached to said base; binding-posts E attached to said base and having means for securing branch wires thereto; fuses I and J secured to said binding-posts A and E; and a two-part clamp designed to be secured over the main wire, one of said parts being arched and recessed to form a solder-chamber, the lateral sides of which form a fitting-rib; means for securing said parts together over said wire; and means for fastening said clamp to said binding-post A, substantially as described.

In testimony whereof we have signed our names to this specification in the presence of two witnesses.

WILLIS M. HALL.
WILSON K. ELDRIDGE.
